Primary Examiner — Brandon M Rosati*Assistant Examiner* — John A Voytek(74) *Attorney, Agent, or Firm* — QuickPatents, LLC;
 Kevin Prince(57) **CLAIM**

I claim the ornamental design for a medallion, as shown and described.

DESCRIPTION

FIG. 1 is a perspective view of a medallion, showing my new design;

FIG. 2 is a top plan view of FIG. 1; and,

FIG. 3 is a front elevational view of FIG. 1, the rear elevational view, left-side elevational view, and right-side elevational view all being identical thereto.

1 Claim, 2 Drawing Sheets(56)
